Inventor:

Joseph Chisholm

United States Patent Office.

JOSEPH CHISHOLM, OF BOSTON, MASSACHUSETTS.

Letters Patent No. 91,521, dated June 22, 1869.

IMPROVED ASH-SIFTER.

The Schedule referred to in these Letters Patent and making part of the same.

To all whom it may concern:

Be it known that I, JOSEPH CHISHOLM, of Boston, in the county of Suffolk, and State of Massachusetts, have invented certain new and useful Improvements in Ash-Sifters; and I do hereby declare the following to be a full, clear, and exact description of the same, reference being had to the accompanying drawings, making a part of this specification, in which—

Figure 1 is a plan of my improved machine;

Figure 2 is a side elevation; and

Figure 3 is a vertical longitudinal section, taken on line $x-x$ on fig. 1.

My invention relates, in the first place, to an improvement in the hopper; and consists in adding to the hopper that receives the ashes and conveys them to the sieve, a movable inclined side, pivoted at the top of the fixed side of said hopper, and provided with a spring, so arranged that when there is no ashes or coal in said hopper, the movable side shall be swung into such a position as to effectually close the mouth of the hopper, and prevent the escape of dust during the operation of sifting.

It also consists in attaching the spring to said movable side of the hopper, in such a manner that its upper end may be moved so as to cause the spring to draw in a line with the pivots on which the movable side is hung, and thereby cause it to be held in such a position as to keep the mouth of the hopper open, when, for any reason, it may be desirable to do so.

My invention relates, in the second place, to the manner of hanging the sieve; and consists in passing the link, by which the end of the sieve next to the gearing is suspended, up through the casing in which the sieve is enclosed, and attaching its upper end to the interior of an inverted cap, by which a longer length of link is obtained without an enlargement of sieve-casing.

It also consists in attaching the links, by which the lower end of the inclined sieve is suspended to the sieve-casing, by means of a screw-eye, bolt, and thumb-nut, so that the angle of the sieve may be readily changed at the will of the operator without opening the case.

My invention relates, in the third place, to the facilities for removing the coal and ashes from the case after they are separated; and consists in the use of a receptacle to receive the ashes, and another to receive the coal, in combination with an inclined vibrating sieve, and a case enclosing the same, and provided with compartments for each receptacle, said compartments being provided with doors to close them, so as to confine all the dust within the case.

It also consists in the use of inclined projecting ledges under the sieve, around the compartment where the ashes are to be deposited, to insure all the ashes being guided into the box or receptacle provided for the purpose.

In the drawings—

A is the sieve-casing, the lower portion of which is divided into two compartments, in which are placed the two boxes B and C, to receive the ashes and coal.

D is an inclined sieve, constructed with its lower end open, so that the coal can roll off and fall into the box C.

The sieve D is suspended by the links a and b , so that it is free to vibrate back and forth when acted upon by the connecting-rod c , connecting it to the crank d , on the shaft E , to which rotary motion is given by the gear-wheels F and G , and the handle e .

The upper end of the link b is attached to an eye-bolt inserted in the cover to the casing, and having a screw-thread cut on its upper portion, and provided with a thumb-nut, b^2 , by means of which the angle of the sieve may be readily changed to suit circumstances.

h h are inclined projecting ledges, placed between the sieve and the box to receive the ashes, and serve to guide the ashes, so that they shall all fall within the box, instead of a portion of them falling on to the edge of the box, and another portion of them falling between the box and the outside casing, where they would soon accumulate, so that the box could not be introduced again when taken out to be emptied.

H is an ordinary hopper, placed upon the top of the casing A, and made fast to it, by means of the hasps i i , in such a manner that it may be readily removed.

I is the movable supplementary side, pivoted at m , so as to be free to swing from that point, and provided with an arm, I' , projecting over the upper edge of the fixed side of said hopper.

J is a spiral spring, attached, by its lower end, to a stud projecting from the fixed side of the hopper, and its upper end attached to a stem, n , which passes through a slot in the arm I' provided for the purpose, and having a collar that rests upon the upper surface of the arm I' .

The tension of said spring, acting upon the arm I' , serves to swing the supplementary side of the hopper into such a position as to close the mouth of the hopper, and prevent the escape of dust through the hopper during the process of sifting.

K and L are doors in the casing A, giving access to the two compartments containing the coal and ash-boxes, and also serve, when closed, to confine the dust within the case.

M is a portion of the top of the case, hinged so as to be easily opened, to enable the operator to have access to the sieve.

The operation of my machine is as follows:

The machine being in the condition shown in the drawings, the ashes and cinders to be sifted are placed in the hopper H, when their weight forces the movable or supplementary side I of the hopper back, and opening the mouth of the hopper, the ashes fall upon

the inclined sieve D, when the tension of the spring J causes the supplementary side I of the hopper to assume its former position, and close the mouth of the hopper, when, if the gear-wheel F be revolved by the handle e, the sieve will have a vibratory shaking motion imparted to it, which will cause the coal and cinders that are too large to pass through the sieve to roll off from the lower end of the sieve and fall into the box C, while the ashes will be shaken through the meshes of the sieve, and fall into the box B, which operation may be repeated until one or both of the boxes B and C are full, when they may be removed from the case A by opening the doors K and L, and, being emptied, they may be replaced, and the doors closed, when the operation may be continued.

What I claim as my invention, and wish to secure by Letters Patent, is—

1. Controlling the action of the yielding supplementary side I, of the hopper H, by the use of the spring J, arranged and operating substantially as described.

2. The general arrangement and combination of the movable inclined sieve D, receptacles B and C, enclosed in the case A, and the hopper H, provided with the yielding supplementary side I, substantially as described.

JOSEPH CHISHOLM.
